GEORGE W. McCANN, OF SPRINGFIELD, OHIO.

Letters Patent No. 60,766, dated January 1, 1867.

IMPROVEMENT IN WATER-WHEELS.

The Schedule referred to in these Letters Patent and making part of the same.

TO ALL WHOM IT MAY CONCERN:

Be it known that I, GEORGE W. McCANN, of Springfield, in the county of Clark, and State of Ohio, have invented certain new and useful Improvements in Water-Wheels; and I do hereby declare the following to be a full, clear, and exact description of the same, reference being had to the accompanying drawings, in which—

Figure 1 is a vertical section through the centre of my wheel, its case, and a portion of the flume.

Figure 2, a plan view of the top of the wheel-case, showing the arrangements of the gates, &c.

Figure 3, a bottom plan of the wheel and case.

Figure 4 is a diagram showing the relative positions of the buckets and ports.

My invention consists, first, in the construction or arrangement of the buckets of the wheel, in connection with the gates; whereby the full power of the amount of water used may be utilized without requiring the wheel to exert the full power due to its size, and whereby the power of the wheel may be graduated to suit the requirements of its service; second, in the construction and operation of the gates. That others may understand my invention, I will particularly describe it.

A is the wheel-case, which also forms a part of the flume, which extends upward from its upper edge, as shown in fig. 1. At the bottom of the case, A, is the bridge, B, composed of two bars crossing at right angles, and securely bolted at their ends to the sides of the case. A screw, C, with a pointed end is inserted through the centre of these bars at their junction, and forms the step for the lower end of the wheel-shaft. The wheel, D, is of that class in which the water passes through in a line as nearly as possible vertical, acting upon a series of ogee buckets. The buckets, E, are disposed in two series or rings, one outside of the other, as shown in figs. 1 and 3, and the two series are separated by the vertical partition F. The number of buckets in each series, as well as the number of series, may be varied to correspond with the size of the wheel or the character of the work, or supply of water. Above the wheel is a partition containing the ports, G, of which there need not be more than half the number of buckets. The ports, G, incline at a different angle from the buckets, so that as the water descends through them, it will strike with its full momentum into the concave or upper curve of the bucket, as is clearly shown in fig. 4. The gate, H, is a flat ring covering the upper ends of the ports, but with spaces, I, which, when brought over the ports, permits the escape of the water to the buckets. Each series of ports is provided with a separate gate, so that one series may be wholly closed, while the other series is wholly or partially open. The pressure or shoot-boards, J, are attached to the under sides of the gates, and extend downward into each port, conforming to the end thereof, so that as the gate is drawn back to uncover the port, the shoot-board will be withdrawn in the same degree, and will with the end of the port form a duct to convey the water to the wheel, without permitting it to be broken up until it has struck the wheel.

My invention is to some extent based upon the idea, that to derive the full measure of power due to a certain quantity of water, it is necessary that the water should be confined, as, for instance, with the port half open the water in rushing through will only half fill the bucket, and will even then be greatly broken into spray. Although the force exerted should theoretically be one-half of that due to the column of water passing through when the ports are entirely open, still it is found to fall far short of that proportion. If the bucket was only half its actual size, and then half the full quantity of water admitted, the theoretical result would be realized. In order to carry out in practice as nearly as circumstances will permit, these ideas, I construct my wheel with two or more series of buckets as described, and I admit the water at the top and vent it at the bottom, because it is disadvantageous to deflect the column of water from its line of movement if it can be avoided. By making the series of buckets independent of each other, the wheel possesses three perfect powers, *i. e.*, first, the inner series alone, second, the outer series alone, third, the two combined, and any imperfect power desired may be obtained by partially opening the gates. The racks and pinions K K and L L, operated by the rods, M, open the gates as required, and the springs, N N, always tending to close the gates, keep them constantly pressing against the pinions in one direction, so that the gate at all times occupies a definite position in regard to its pinion, and the opening of the port does not depend upon any back-lash or play between the cogs of the rack and pinion. The hollow stand-shaft, O, with the bearing, P, at its upper end, protects the driving-shaft, R, of the wheel, D, from contact with the water of the flume, and affords it support and a steady bearing for its

upper end, so that no change in position of the parts of the flume in respect to the wheel-case, A, will throw the driving-shaft out of truth.

I am aware, that Albert A. Wood, of Manlius, Onondaga county, in the State of New York, has invented a movable shoot-board, by which the stream of water is conducted so as to impinge upon the floats of the wheel, always at the same angle, whether the port be wholly or partially opened, and therefore do not claim said device.

Having described my invention, what I claim as new, and desire to secure by Letters Patent, is—

1. The wheel D, with two or more series of buckets, substantially as described, in combination with the independent gates H H', for the purpose set forth.
2. In combination with the gates H H', the springs N N, substantially as and for the purpose set forth.

GEO. W. McCANN.
